UNITED STATES PATENT OFFICE.

SADATAKA TESHIMA, OF CHICAGO, ILLINOIS.

CLOSING AND DISCHARGING MEANS FOR MUCILAGE BOTTLES.

Application filed July 31, 1925. Serial No. 47,200.

My invention pertains to improvements in closing and discharging means for mucilage bottles, and has for its main object to provide closing means for such a bottle which will positively cover and seal the mucilage discharging means or sponge so that it will not dry out, and will also permit ready use of the sponge and application of mucilage at any time. Another object is to provide an inexpensive and efficient construction.

Other objects will appear hereinafter.

The invention consists in the combinations and arrangements of parts hereinafter described and claimed.

The invention will be best understood by reference to the accompanying drawings forming a part of this specification, and in which,

Fig. 1 shows a form of my invention in connection with a mucilage bottle.

Fig. 2 is an enlarged vertical sectional view of my invention.

Fig. 3 is a horizontal sectional view taken on line 3—3 of Fig. 2, looking in the direction of the arrows.

Fig. 4 shows another form of the invention.

Fig. 5 is an enlarged vertical sectional view thereof.

Fig. 6 is a horizontal sectional view taken on line 6—6 of Fig. 5.

Fig. 7 is an inverted horizontal sectional view taken on line 7—7 of Fig. 5, and

Fig. 8 is a detailed view of the combination washer and sleeve.

In Figs. 1 to 3 inclusive I have shown a form of my invention in connection with a mucilage bottle 10 provided with a threaded neck 11. A sponge or porous member 12, for feeding and applying mucilage or similar fluids, is mounted in neck 11 by means of pins 13 extended through member 12, the ends of said pins being seated between washers or gaskets 14 and 15 which are supported on top of the neck 11. A threaded collar 16 is fastened on said neck and is provided with an inwardly extending shoulder 16' for holding said washers and thereby the pins and sponge in position,

and a sleeve 17 is formed on the upper part of said collar for embracing a part of the sponge to steady the same.

I provide means for sealing the sponge or member 12 air-tight, so as to prevent the same from drying out while not in use. This means preferably comprises a cap 18 of

rubber or similar air-proof and moisture-proof material, which is mounted over the sleeve 17 and closes said sponge air-tight on the bottle thereby preventing drying out 60 while not in use.

I preferably also provide a closing member or hood 19, provided with a curved and slightly resilient portion 19' engaging a suitable portion 10' on bottle 10, for housing 65 and protecting the preceding elements 12 to 18 inclusive. The hood 19 is preferably constructed of metal or some firm rigid material.

In Figs. 4 to 8 inclusive I have shown another form of my invention in connection with a mucilage bottle 20 having a neck 21 thereon; a sponge or suitable porous member 22, for feeding and applying mucilage or similar fluid, is mounted in the neck 21 by the use of pins 23 extended through the sponge and having their ends resting on a washer or gasket 24 seated on neck 21. A washer 25, with a sleeve portion 25' for embracing a portion of the sponge, rests on 75 pins 23. A collar 26 engages a gasket 27 seated in the groove on neck 21, and is provided with a sleeve portion 26' surrounding portion 25' of washer 25, said collar with its neck portion retaining members 22 to 25 80 in position.

This form of invention is also provided with sealing means for the sponge, which preferably includes a cap 28 of rubber or similar air-proof and moisture proof material, said cap firmly embracing sleeve portion 26' and retaining the sponge 22 moist and soft and always ready for use. A hood 29 of metal or other firm and rigid material is mounted over the cap and collar for protecting the same and is held in position by firmly engaging dents or teeth 30 which are pressed outwardly on said collar.

It is apparent from the above disclosure that a mucilage bottle provided with my closing and discharging means will have a soft and pliable sponge for properly feeding and applying the mucilage at all times, and that the air is effectively prevented from reaching the sponge, when the device is not 100 in use, thus positively preventing the sponge from becoming crusted with mucilage and hard, as is the case with the feeding devices on mucilage bottles which are now on the market.

While I have illustrated and described the preferred form of construction for carrying

my invention into effect, this is capable of variation and modification without departing from the spirit of the invention. I, therefore, do not wish to be limited to the 5 precise details of construction set forth, but desire to avail myself of such variations and modifications as come within the scope of the appended claims.

Having described my invention, what I 10 claim as new and desire to secure by Letters Patent is:

1. In combination with a bottle, porous means mounted in the neck of said bottle, pins extending through said porous means, 15 washers holding the ends of said pins, and a collar holding said washers and pins on said neck.

2. In combination with a bottle, porous means mounted in the neck of said bottle, 20 wire pins extending through said porous means, washers and a collar for holding said pins and porous means in position, a rubber cap for covering said porous means air-tight, and a strong rigid hood to cover 25 the aforesaid elements.

3. In combination with a bottle having an

externally threaded neck, a porous member in said neck and protruding therefrom, pins extending through said porous member and overlying said neck, washers on said neck 30 engaging the ends of said pins, a collar threaded on said neck and provided with a shoulder engaging said washers, said collar being extended to partially embrace the protruding portion of said porous member; and 35 a moisture-proof cap removably engaging the projecting portion of said collar.

4. In combination with a bottle having a threaded neck, a collar threaded on said neck and having an inturned shoulder and 40 an upwardly extending sleeve, a sponge extending from said neck through said sleeve, pins extending through said sponge, pliable washers engaging the ends of said pins and being retained in position between said shoulder and the bottle neck, a rubber cap on said sleeve to cover the sponge air-tight, and a strong rigid hood to cover said cap and collar.

In testimony whereof I have signed my 50 name to this specification.

SADATAKA TESHIMA.
